UNITED STATES PATENT OFFICE.

HERBERT B. SAUNDERS, OF NEW YORK, N. Y.

METHOD AND APPARATUS FOR FLOATING AND REPAIRING STRANDED VESSELS.

1,089,967.

Specification of Letters Patent. Patented Mar. 10, 1914.

Application filed September 9, 1913. Serial No. 788,930.

To all whom it may concern:

Be it known that I, HERBERT B. SAUNDERS, a citizen of Great Britain, residing at New York, in the county of New York and State of New York, have invented certain new and useful Improvements in Methods and Apparatus for Floating and Repairing Stranded Vessels; and I do declare the following to be a full, clear, and exact description of the invention, such as will enable others skilled in the art to which it appertains to make and use the same.

This invention relates to method and apparatus for raising or removing stranded or sunken vessels and more particularly for the floating of stranded or partially submerged vessels where the injury causing the wrecked condition is due to the leakage of water into the hold either through a hole stove therein or through openings formed by other causes.

In its broad comprehension this improved method involves the treatment of the wrecked vessel to render the compartment or hold where the injury has occurred air-tight or substantially so; the introduction into said hold or compartment of air under pressure to expel the water; in the provision of means for permitting access of the workmen into the hold while the pressure is maintained therein and in means for overcoming the pulsation caused by the contact of the compressed air and the water at the acute point of the wound in the vessel.

With these and other objects in view, the invention consists of certain novel features of construction, and the combination and arrangement of parts as will be more fully described and claimed.

In the accompanying drawings: Figure 1 represents a side elevation partly in section of a stranded vessel resting on a rock with a hole stove in one of the compartments or holds and the latter filled with water; Fig. 2 represents a transverse section showing the compartment rendered air-tight to receive the air pressure and braced to stand the internal strain; Fig. 3 represents an enlarged sectional view of one of the equalizing pipes fitted directly over a wound or opening in the bottom of a compartment; Fig. 4 is a top plan view of the steel hatch plate; Fig. 5 is an enlarged detail sectional view taken on the line 5—5 of Fig. 4 showing the air lock chamber in section; Fig. 6 is a side elevation partly in section of the 55 air receiver; Fig. 7 is a transverse section thereof taken on the line 7—7 of Fig. 6.

In the embodiment illustrated a vessel hull 1 is shown divided into compartments 2 one of which has a hole 3 stove therein and 60 which compartment is filled with water causing the vessel to settle. The leaking compartment is provided with the usual hatchway 4.

In applying this improved method the 65 first step is to brace or strengthen the top or deck portion of the hold containing the leaky compartment so that it will withstand without injury the internal pressure to which it will be subjected when air under 70 pressure is introduced. This strengthening may be accomplished in any appropriate manner. The compartment 2 having the hole 3 therein is next closed air-tight by the application to the hatchway 4 of a steel 75 hatchway plate 5. This plate 5 is applied against the edge of the coaming on the underside thereof, a rubber gasket being interposed to form a tight joint. In applying the plate or covering 5 and its gasket, suitable 80 means should be employed for holding the plate temporarily against the coaming before the air pressure is turned on. After the plate 5 has been drawn into position, the inner side of the joint may be protected with 85 a suitable cement, if desired or found necessary. After the air pressure has been turned on it will act to bind the plate tightly against the coaming and effect an air-tight joint. If there are other communications of 90 the injured compartment with the outside such as port holes, funnels, etc., these are also closed air-tight by appropriate means. The next step in the method is to provide for the access into the compartment of workmen while the pressure is maintained therein so that an inspection of the injured compartment may be made and, if necessary, the 95 leaks repaired. This is effected by the application preferably to the hatchway plate 5 100 of an air lock 8 such as is employed in connection with caissons and consisting of a chamber 9 here shown cylindrical with a door 10 communicating with the outside and a second door 11 communicating with the 105 hold. Care should be taken to see that the

joints and doors at the top and bottom of the lock are made workable and air-tight. Suitable inlet and outlet valves 12 and 13 are fitted in the lock and are provided with electric light bulbs. This hatchway plate 5 is preferably equipped with high and low air pressure connections 14 and 15, steam and water fittings 16 and 17 and electric light and telephone fittings 18 and 19 whereby the work within the compartment may be facilitated avoiding the necessity of the workmen going in and out. The next step in the method consists in introducing air under pressure into the compartment in order to expel the water which has leaked thereto. This may be accomplished in any appropriate manner. As shown in Fig. 1 an air compressor 20 is mounted on the upper deck or in any appropriate location and is driven by a suitable engine, the compressor being connected by a pipe 21 with an air receiving tank 22 having a coil of water pipe 23 disposed therein for the passage of cold water designed to chill or cool the air passing through the tank out of the pipe 24 and passing into the leaking compartment. A safety valve 25 is disposed in the pipe 21 and an equalizing pipe 26 is fitted on said valve so that in the event of the air pressure rising suddenly which often occurs when the wounded parts of the vessel under repair on the inside are covered, the excess air will immediately escape and the required or regular pressure be maintained within the compartment. This receiver 22 is strongly built to withstand with safety the pressures of air to which it must be subjected and the coils of water pipe therein are connected with a small circulating pump (not shown), for pumping chilled water through the coils within the tank for cooling the air therein. If the air was forced directly from the compressor into the hold or compartment without passing through such receiver, it would in a very short time after entering the compartment under pressure become very dense or fogged thereby greatly interfering with the work of the men if not rendering it impossible. The use of the receiver above referred to avoids this difficulty.

It has been found that at the point of contact of the compressed air and the water within the injured compartment a very vigorous pulsation is set up which renders it nearly impossible to obtain the adhering of the concrete or other patch to the steel plates and hence to overcome this difficulty internal equalizing pipes 26 have been introduced. These equalizing pipes 26 are each formed from an ordinary three and a half inch iron pipe about three feet long, more or less, and having a flanged socket 27 screwed to the lower end thereof. The flange 28 of this socket is provided with a plurality of apertures 29 into which wooden blocks 30

about two inches in length are driven and which are designed to rest on the steel plate at the bottom of the compartment around the wound or opening 3 therein to properly space the flange 28 from said plate or bottom of the compartment to permit the air and water to pulsate freely under this flange and to pass up into the pipe 26. Under this flange 28 a lead jacket or apron 31 is fitted, the equalizing pipe 26 being placed in a vertical position immediately over the wound 3 and the outer edges of the lead jacket are carefully pinned down onto the steel plate in which said wound occurs. The upper end of the pipe 26 is left open and the air and water are allowed to play therein without interfering with the concrete patch 32 which is being laid over the wound on the lead jacket 31. Hence the objectionable pulsations above referred to are confined within the restricted area of said pipe or pipes 26. As soon as the concrete patch has hardened the upper end of the pipe is fitted with a cap 33 preferably screwed thereon thus closing the equalizer and making a perfectly tight patch which will withstand any pressure to which the ordinary vessel is subjected. After the equalizing pipes 26 have been placed in position, any desired number of which may be used, the compressed air is admitted to the wounded compartment through the pipe 24 and the water will be expelled through the opening 3. While the pressure is maintained workmen, through the medium of the air lock 8, may enter the hold and make such repairs as may be necessary. When the wounds have been repaired to prevent the further access of water into the compartment the water remaining may be removed in any suitable manner either by pumps or by blowing it out through the scuttle pipes.

I claim as my invention:

1. A method of treating leaking stranded vessels which consists in sealing substantially air-tight the usual communication of the leaking compartment with the outside, permitting entrance to said compartment under air pressure in excess of that of the atmospheric air, introducing air under pressure into said compartment to expel the leaking water, and confining to a restricted area in said compartment the pulsations caused by the contact of the air and water within the compartment.

2. A method of treating leaking stranded vessels which consists in sealing substantially air-tight the usual communication of the leaking compartment with the outside, permitting entrance to said compartment under air pressure in excess of that of the atmospheric air, introducing air under pressure into said compartment to expel the leaking water, cooling the compressed air before admitting it to the compartment, and

confining to a restricted area the pulsations caused by the contact of the compressed air with the water.

3. A device for confining to a restricted area pulsations caused by the contact of compressed air and water, comprising a pipe having a flanged base provided with a plurality of apertures, spacing elements arranged in said apertures for holding said base spaced from its support, and an apron disposed between said base and the support on which said base rests.

4. A device for confining to a restricted area the pulsations within a compartment caused by the contact of compressed air and water comprising a pipe having a flanged base provided with a plurality of apertures, spacing elements arranged in said apertures for holding said base spaced from its support, an apron adapted to be clamped to the

support on which said base rests, and removable means for closing the upper end of said pipe.

5. The combination with a vessel having an opening in one wall thereof, of an equalizing device comprising a pipe having a flanged base disposed over said opening, spacing elements extending from the lower face of said base and adapted to rest on the wall of said vessel around said opening, and a lead apron secured to said wall and extending under said flanged base.

In testimony whereof I have hereunto set my hand in presence of two subscribing witnesses.
